INVENTOR

James C. Blake

UNITED STATES PATENT OFFICE.

JAMES C. BLAKE, OF WARREN, ASSIGNOR TO ROBERT BARTON, OF PROVIDENCE, RHODE ISLAND.

DETACHABLE BUTTON.

SPECIFICATION forming part of Letters Patent No. 250,130, dated November 29, 1881.

Application filed September 7, 1881. (No model.)

To all whom it may concern:

Be it known that I, JAMES C. BLAKE, of Warren, county of Bristol, and State of Rhode Island, have invented a new and useful Improvement in Detachable Buttons; and I do hereby declare that the following specification, taken in connection with the accompanying drawings, forming a part of the same, is a full, clear, and exact description thereof.

5 My invention relates particularly to that class of buttons in which the shoe is hinged to the post, so that it can be turned from a position parallel with the button-head to a position parallel, or nearly so, with the post.

10 My improvement consists in providing the shoe of the button with a plate having ears which project above the surface of the plate and cover the ends of the pin member of the hinge, so as to prevent said pin from becoming accidentally displaced.

15 Referring to the drawings, Figure 1 represents, in partial section, a button embodying my improvement. Fig. 2 shows, in perspective, the post, the hinge member of the shoe, and the eared plate detached from each other and also combined.

20 A is the button-head, to which the post B is attached, the said post having an enlarged end, b, which forms its pivotal member. C is the shoe, which is composed of a shell, 25 c, and a centrally-perforated disk, D, secured thereto, the said disk having lugs d d, which form the pivotal members of the shoe.

25 E is the pivotal pin, which passes through the lugs d d and the post end b and hinges the shoe to the post.

30 F is a leaf-spring, (shown in section in Fig. 1,) which bears upon the disk D and engages the post end b, so as to retain the shoe in a position

parallel with the button-head, and also parallel, or nearly so, with the post when the shoe is turned, in order that the button may be applied or removed.

35 G is a plate secured to the shoe by solder, or in any preferred manner, as by turning the shell c over upon it, as shown in Fig. 1. The plate G is centrally perforated, and is provided with ears g g, which project above its surface and cover the ends of the pin E, thereby concealing the same, as shown in Fig. 1, 40 and preventing said pin from being accidentally displaced.

45 By the use of my improvement upon a button the shoe is securely retained against loss. It also presents a more finished appearance, as 50 the ends of the pivotal pin, as well as the spring, are concealed from view.

55 Should the removal of the pin become necessary or desirable, the ears g g may be turned down and the pin be removed without damage 60 to the article.

65 What I claim as my invention, and desire to secure by Letters Patent, is—

As an improved article of manufacture, a detachable button composed of a head, an attached post having an enlarged free end, a shoe provided with a disk, D, having pivotal members d d, a pivotal pin passing through the members d d and through the enlarged post end, a spring bearing upon the disk D 70 and engaging the post end, and a plate, G, secured to the shoe and having ears g g, which cover the ends of the pivotal pin, substantially as and for the purposes specified.

JAMES C. BLAKE.
